UNITED STATES PATENT OFFICE.

GAIL MERSEREAU, OF NEW YORK, N. Y., ASSIGNOR TO CHEMICAL DEVELOPMENT COMPANY, A CORPORATION OF MAINE.

APPARATUS FOR PRODUCING DIOLEFINS.

1,308,802.

Specification of Letters Patent.

Patented July 8, 1919.

Application filed September 14, 1912, Serial No. 720,363. Renewed December 13, 1918. Serial No. 266,651.

To all whom it may concern:

Be it known that I, GAIL MERSEREAU, a citizen of the United States, residing at New York, in the county of New York and State of New York, have invented certain new and useful Improvements in Apparatus for Producing Diolefins, of which the following is a specification.

This invention relates to processes of and apparatus for producing diolefins; and it comprises a method wherein a gas rich in olefins and containing diolefins is treated to remove such diolefins and thereafter heated to produce a further quantity of diolefins, such removal of diolefins and heating to produce more being repeated as many times as may be desired; and it also comprises an organization of apparatus elements comprising consecutively arranged means for producing a gas rich in olefins and diolefins, means for removing diolefins therefrom, means for heating the treated gas to produce more diolefins and means for recovering the newly produced diolefins; all as more fully hereinafter set forth and as claimed.

In another and copending application, Serial No. 713,585, filed Aug. 6, 1912, is described and claimed a method of producing gas rich in olefins wherein heavy oil vapors are exposed for a limited time, as by passing through a relatively short and narrow tube, to a regulated heating at a temperature around 700° C. under conditions not producing a total gasification of such oil; that is, permitting a substantial amount of heavy oil vapors to pass through with the gas produced. The oil vapors are condensed out of the gas and returned in admixture with fresh oil to the heating zone. It has been found that by passing heavy oil vapors through a comparatively short and narrow pre-heated tube in this manner a gas can be produced carrying 45 to 50 per cent. total olefins, 4 or 5 per cent. acetylenic gases, 4 to 5 per cent. diolefins with a residue consisting mainly of saturated gases, such as ethane. The best results were attained with iron or steel tubing ranging between 0.25 and 1.5 inch internal diameter heated within 20 or 30 degrees on either side of 700° C. At 650° C. the action is slow and at 750° perhaps too rapid, while about 800° C. is a danger line which should not be exceeded. Absence of coky carbon is necessary for smooth thermolysis, since it exercises an un-

desirable catalytic action upon the gas, producing more carbon and causing the tubes to plug up. Softer forms of carbon, such as soot and lampblack, do not have this action to such an extent. With proper regulation of conditions, the oil is gasified without formation of tar or carbon.

In this prior work it was found that while rich olefinic gas could be made under the stated conditions within rather wide limits in the length of the heated zone, that is, with great variations in the time-heat factor, yet there were important variations in the mutual ratios of the various unsaturated gases to each other. A good conversion to form olefinic gases can be attained with no more than 6 inches of travel through a heated zone while 90 inches and more of travel are not injurious under proper heating and other conditions. With a shorter length of travel, up to say 30 to 45 inches, the proportion of diolefins is about 4 to 5 per cent. of the total gas and the ethylene is present in much larger amount than propylene and the butylenes. With a longer travel of the oil vapors through a heated zone, up to say 90 inches, the proportion of propylene relative to ethylene rises and the percentage of diolefins also increases up to about 8 per cent.

I have now found that this proportion of about 8 per cent. represents a maximum limit; a limiting "partial pressure;" that the formation of diolefins goes on till about this percentage is reached, (the exact percentage varying somewhat with temperature and other conditions) and then ceases. This formation of diolefins appears to be at the expense of the olefins proper. If the heating be interrupted when this maximum is reached, the gas cooled to remove oil vapors and the diolefins removed and recovered, upon reheating the gas to about the temperature at which it was originally formed a fresh crop of diolefins is formed. Here again the maximum limit seems to be about 8 per cent. On removing the newly produced diolefins and once more heating the residual gas, more are produced, the limit again seeming to be about 8 per cent. Repetition of the treatment will give a fourth crop; but this time the amount is generally only about 6 per cent. Subsequent treatments ordinarily are hardly worth while. The residual gas after the described pro-

duction and removal of diolefins still has a high heating and lighting value; and some portion of it may be usefully employed in furnishing the heat necessary in the various operations. A less valuable gas may of course be used instead for heating purposes.

In the reheating of the gas to produce successive crops of diolefins it is not necessary to have oil vapors in the sphere of reaction and their use introduces practical complications in the operation. Except in the original formation of the gas therefore I ordinarily do not heat in the presence of oil vapors. In the reheating, the temperatures may advantageously be, as in the original production of the gas, around 700° C. Coky carbon is better absent.

While my process of removing diolefins and heating to produce more diolefins is applicable to any gas rich in olefins and containing diolefins, I regard it as particularly applicable to the gas produced as described. As a gas making material may be used any crude petroleum or analogous hydrocarbon material. Gas oil or other still residuums substantially freed of low-boiling constituents are very advantageous. Petroleums containing cyclic hydrocarbons on gasification produce more or less benzol, toluol, xylols, etc., and therefore less amounts of olefins, and, concomitantly, less amounts of diolefins per gallon of oil. However these aromatic hydrocarbons are readily separable from the diolefins and are commercially valuable. In the described way of producing the olefinic gas from gas oil with the subsequent production of several crops of diolefins under the present invention, over a quarter of the oil may be converted into diolefins.

Ordinarily in each heating passage of the oil vapors, or gas, I prefer to use about 80 to 90 inches of rather narrow tubing, say 0.25 to 0.75 inch internal diameter. While 45 terra cotta, copper, bronze, aluminum, etc., tubes may be used they have no special advantage over steel or iron. Catalysts are not necessary for successful operation. Coky carbon should be absent and should 50 it form, the operation should be interrupted to remove it. For this reason it is desirable to arrange the heating tubes or tube retorts so that they can be readily cleaned, as by thrusting a cleaning rod through. As many 55 tubes or tube retorts may be employed operating in parallel as may be desired; it being better to gain capacity in this way rather than by increasing the diameter of the tubes.

The diolefins formed in the successive crops may be removed and recovered in any desired way, as by scrubbing with sulfuric acid of appropriate strength and temperature, by combining with SO_2 which forms compounds readily resolved by heat, by compression of the gas, by chilling or by the use

of a cold wash oil. The cold wash oil is an advantageous means since it readily yields or releases its absorbed diolefins in vapor form on warming. Gas oils or heavy liquid residues rich in aromatic series components 70 may be advantageously used as a wash oil since such oils can be obtained having a good absorptive power for diolefins and a freezing point sufficiently low to permit efficient chilling. The same quantity of wash 75 oil may of course be used over and over again, circulating cyclically through absorbers and releasers. Where compression of the gas is used in recovering the diolefins, it is advantageous to use a little cold 80 oil also. While the diolefins particularly contemplated in this invention have boiling points ranging from 0° to 56° C., yet because of their relatively high vapor tension and their small proportion in the gas it is 85 difficult to remove them all by a simple compression or a chilling without the use of some such expedient as a portion of cold oil as an absorbing solvent. The use of chilled oil as a washing liquid in a device like a 90 scrubber or a column still is quite satisfactory and is relatively simple. The same current of chilled oil may be used for operating a plurality of absorbers.

In the accompanying illustration I have 95 shown, more or less diagrammatically in vertical section, some parts being in elevation, a typical organization of apparatus elements within the present invention and useful in the operation of the described 100 process. In this showing,

Element 1 is a suitable furnace chamber. In this chamber are, as shown, four banks, A, B, C, and D, of tube retorts, the retorts of A serving to transform oil into gas containing olefins and diolefins, and those of B, C, and D being reheaters, or diolefin generators. In each bank, there may be as many sets of tube retorts operating in parallel as may be desired. The tube retorts, as shown, in all the banks are similar and consist of a length 3 of narrow tubing from 0.25 to 1 inch internal diameter connected with another length or return tube 4 by vertical connection 5. Each length 115 may have an extension of 40 or 50 inches within the furnace chamber. Caps 6 and 7 at the ends of each tube enable a cleaning rod to be thrust through.

Oil is supplied from reservoir 8 by means 120 of pump 9 to main 10 which may feed any number of tube retorts operating in parallel in bank A. The connection between the main and each tube retort is valved at 11, permitting any individual tube retort to be 125 cut out for cleaning without interrupting the operation of the others in the bank. The tube retorts are, as shown, best supplied with liquid oil or given a "flooding feed" as this is more convenient than the 130

generation of oil vapors elsewhere with the heavy, high-boiling oils most advantageously used in the present invention. The gas formed in the tube retorts of bank 5 A and the excess of oil vapors pass into main 12. Using heavy oils as raw material this may be simply air-cooled, but it gives an economy of space to use a surface condenser such as 13 of a well known type. 10 This may be fed with oil through 14, the oil passing through and going to the reservoir through pipe 15. The condensate drains back into the reservoir where it mixes with the fresh oil and is returned for passage 15 through the retorts in admixture with such oil. The condensed oil always contains some cracked products of the nature of gasoline and kerosene, but there is usually a larger proportion of unchanged original oil and the volatile cracked products are 20 absorbed and held back by this oil; they are scrubbed out. The gas passing the condenser is urged by pumps or impellers 17, which may put it under as much pressure as 25 may be desired, past chiller 18 into absorber 19. The chiller is best given a slight slant toward the absorber to facilitate drainage thereto. The absorber may be any ordinary type of scrubber or it may be constructed 30 something like a column still with cups and plates to facilitate intimate contact of the gas with the cold oil supplied through inlet 20. The gas freed of its diolefins and quite cold passes through 21 to a heat inter- 35 changer 22 and thence to a gas main 23 supplying the tube retorts of bank B. In the tube retorts of this bank the gas is re-heated and diolefins produced. The hot gas goes to main 24 and thence through the heat 40 interchanger and conduit 25 past pump or impeller 26 and chiller 27 to absorber 28. Here it is once more treated with chilled oil to remove diolefins. After scrubbing it goes through conduit 29 and heat inter- 45 changer 30 to main 31 supplying the retorts of bank C. In this bank it is once more heated to produce more diolefins. It passes from bank C to main 32 and thence through the heat interchanger and conduit 33 past 50 impeller 34 through chiller 35 to absorber 36. Here it gives up its new charge of diolefins to the chilled oil and is then sent through conduit 37 and heat exchanger 38 to main 39 supplying the tube retorts of bank 55 D. From these retorts it passes to main 40, thence through conduit 41 and the heat interchanger past impeller 42 and chiller 42^a to and through absorber 43 to remove the diolefins. 60 The operation may be repeated, but in general after four heating operations the amount of olefins diminishes to such an extent that the production of diolefins becomes quite small and as a rule at this point the 65 residual gas, which is still of a desirable nature for heating and lighting, is best used for such purposes. It may however be passed over a catalyst, such as nickel or palladium, or both together, on a carrier, such as petroleum coke, at about 200° C. to 70 produce more olefins and then the described heating and absorbing operations repeated. 75 The gas passing the fourth absorber shown is still rich in ethane and other gases of high heating and lighting value. It may be sent through conduits 44 and 45 to any suitable place of use; or it may be treated as described. A portion may be sent through 46 to supply heat in the furnace. 80 The diolefins in the gas from retorts A are not usually as pure as those recovered from the reheated gas in later operations. The diolefin recovered in scrubbers 43 and 36 may be substantially pure divinyl. In 85 19, some aromatic hydrocarbons may be taken up. The gas-making operation does not form the aromatic hydrocarbons from the aliphatic but if the original oil contains such hydrocarbons they may reappear in the gas. For this reason it is usually 90 worth while recovering the diolefins from 19 separately from those recovered later. For this purpose this absorber may be connected to a separate still 47 having a heat interchanger 48 acting as a "goose". In lieu 95 however of sending condensates back into the still, as is usual with such an interchanger, they may be removed by outlet 49. This will dispose of most of the gasolines or 100 benzols which go forward. The uncon- 105 densed vapors pass out through pipe 50 to pump 51 where they are liquefied to form commercial diolefin, which may be packaged in drums. 110 The still may be run at a temperature of about 70° to 80° C. The wash oil from the still or releaser (47) passes by pump 52 to and through cooler 53, where it may be cooled by water and thence by conduit 54 to chiller 55 where its temperature may be 115 lowered to about -15° C. by circulating brine or calcium chlorid solution. Thence it passes to and through the series of absorbers. A special valved pipe (20) may lead a portion to the first absorber in series (19) 120 to enable its independent operation. When this independent operation of the absorber operating on the original oil gas is desired, a special still 56, provided with heat interchanger or "goose" 57, of ordinary construction may be used. Vapors from this may be passed through outlet 57+^a to a liquefying pump (not shown) to produce diolefins 125 rich in divinyl. The chilled oil passes from one absorber to another, taking up diolefins as it goes, the connection between the absorbers being designated 58. A special valved connection 59 enables the absorber for reheated gas and the absorber (19) for 130 oil gas to be used together. In this event,

the still just described (56) is not used. Brine or calcium chlorid may be chilled in refrigerator 60 and sent by pump 61 and conduit 62 through the oil chiller (55) and the 5 successive gas chillers back to the refrigerator.

Some oils leave a carbonaceous residue on evaporation, this coming apparently at least in part from naturally contained free carbon; and this carbon should be removed from the oil feed end of the tube retorts of bank A as it accumulates in using such oils. This carbon does not have the same prejudicial catalytic effect as the hard coky carbon 10 formed, apparently by the decomposition of methane, by heating gases to high temperatures.

What I claim is:—

1. The combination with a retort, of heating means therefor adapted to maintain it at a uniform low heat to convert petroleum into gas, means for recovering unchanged oil vapors from such gas, means for recovering diolefins from the treated gas, means 20 for reheating the gas to produce a further quantity of diolefins and means for recovering such further quantity.
2. In a diolefin making plant a narrow tube, means for supplying oil thereto, means 25 for heating the tube, means for cooling gas coming therefrom to recover residual oil, means for recovering diolefins, means for transmitting the gas through another narrow tube and means for recovering diolefins 30 from the gas issuing from such other tube.
3. In a diolefin plant, the combination with a retort comprising a plurality of tubes, of single means for heating all said tubes, means supplying oil to said retort, in 35 excess of the amount permanently volatilized by said heating means, means condensing and removing excess oil from the gas produced, means for removing diolefins from said gas, a second retort also comprising a plurality of tubes, connections leading the 40 treated gas through said second retort, and means beyond said retort for removing diolefins.

4. In a diolefin plant, a plurality of tube retorts arranged in series, means for heating 50 such retorts, means for passing oil through the first retort, means connected with and beyond the retort for condensing out oily bodies from the gas produced, means for recovering diolefins from such gas, means for 55 returning the gas through the succeeding retorts and means beyond each such succeeding retort for recovering diolefins from the emerging gas.

5. In a diolefin plant, a furnace chamber, 60 a series of tube retorts therein, means for supplying oil to one such retort, means for condensing and removing oil from the gas produced therein, means for removing diolefins from such gas, connections leading the 65 treated gas back to another such retort and means connected with and beyond such retort for removing diolefins.

6. In a diolefin plant, a plurality of retorts arranged in series, connections includ- 70 ing a scrubbing device for passing gas from one retort to the next, and means for supplying chilled oil to such scrubbing device.

7. In a diolefin plant, a plurality of retorts arranged in series, connections includ- 75 ing a scrubbing device between successive retorts, and means for supplying chilled oil to such scrubbing device.

8. In a diolefin plant, a furnace chamber, a series of tube retorts therein, means for 80 supplying oil to one such retort, means for condensing and removing oil from the gas produced therein, means for removing diolefins from the gas produced therein, means for dissolving out diolefins from such gas, 85 connections leading the treated gas back to another such retort, means beyond such retort for dissolving out diolefins, and means for recovering diolefins from the solution in which they are contained.

In testimony whereof, I affix my signature in the presence of two subscribing witnesses.
